(57) **CLAIM**

The ornamental design for an overhead carrying rack for an ATV, substantially as shown and described.

DESCRIPTION

FIG. 1 is an elevational view of my new overhead carrying rack for an ATV taken from a front thereof.

FIG. 2 is a pictorial view of my new overhead carrying rack for an ATV taken from a point above, to one side and to a rear thereof, and shown at a reduced scale to the scale shown in FIG. 1.

FIG. 3 is an elevational view of my new overhead carrying rack for an ATV taken from one side thereof. An elevational view taken from an opposite side would be a mirror image of the view of FIG. 3.

FIG. 4 is an elevational view of my new overhead carrying rack for an ATV taken from above; and,

FIG. 5 is a pictorial view of my new overhead carrying rack for an ATV taken from above, to one side and a front thereof, and shown at a reduced scale to the scale shown in FIGS. 1 and 3.

The dashed line showings of U-bolts in all the drawings, and the dashed line showings of an ATV in FIG. 5 are for illustrative purposes and environmental purposes only, and do not form a part of our new design.

1 Claim, 5 Drawing Sheets

FIG. 1

FIG. 2

FIG. 3

FIG 4
